NEEDLE HUB FOR A HYPODERMIC SYRINGE

Donald A. Hamilton, La Crescenta, Calif., assignor to Pharmaseal Laboratories, Glendale, Calif., a corporation of California

Filed Feb. 19, 1965, Ser. No. 83,903

Term of patent 14 years

(Cl. D83—12)

FIG. 1.

FIG. 2.

FIG. 3.

FIG. 4.

FIG. 6.

FIG. 5.

FIG. 7.

FIGURE 1 is a perspective view of the needle hub for a hypodermic syringe;

FIGURE 2 is a front view of the needle hub for a hypodermic syringe;

FIGURE 3 is a rear view of the needle hub for a hypodermic syringe;

FIGURE 4 is a top view of the needle hub for a hypodermic syringe;

FIGURE 5 is a side view of the needle hub for a hypodermic syringe;

FIGURE 6 is a fragmentary view partially in section of the rear portion of the top view of FIGURE 4; and

FIGURE 7 is a fragmentary view partially in section of the rear portion of the side view of FIGURE 5.

The broken line structure indicating the sharp cannula member in FIGURE 1 is shown for illustrative purposes only.

The characteristic feature of the design resides in the

fragmentary, helically disposed, thread-like segments spaced inwardly on the rear end of the body and projecting in a diametrically opposed relation as shown.

I claim:

The ornamental design of a needle hub for a hypodermic syringe, as shown and described.
